United States Patent Office

Des. 215,592
Patented Oct. 14, 1969

215,592

VEHICLE

Jesse R. Birchard, Walled Lake, Mich., Albert D. Mortrude, Pompano Beach, Fla., and Ray C. Conner, Battle Creek, Mich., assignors to Clark Equipment Company, a corporation of Delaware

Filed Sept. 20, 1968, Ser. No. 13,622

Term of patent 14 years

Int. Cl. D12—09

U.S. Cl. D14—3

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIGURE 1 is a right front quarter perspective view of a vehicle, showing our new design;

FIGURE 2 is a right side perspective view thereof;

FIGURE 3 is a left side perspective view thereof;

FIGURE 4 is a right rear quarter perspective view thereof;

FIGURE 5 is a rear perspective view thereof with the tailgate portion closed;

FIGURE 6 is a rear perspective view thereof showing the tailgate portion open;

FIGURE 7 is a left front quarter perspective view of a modified form thereof;

FIGURE 8 is a left side perspective view of the vehicle shown in FIG. 7;

FIGURE 9 is a right side perspective view thereof;

FIGURE 10 is a rear perspective view thereof showing the tailgate closed;

FIGURE 11 is a rear perspective view thereof showing the tailgate open;

FIGURE 12 is a plan view of the vehicle shown in FIGS. 1-6; and

FIGURE 13 is a plan view of the vehicle shown in FIGS. 7-11.

The dominant features of our design reside in the portions shown in full lines.

We claim:

The ornamental design for a vehicle, as shown and described.
